HANGER FOR BOOKS

John Kemble Bolton, Chatham, and Gustav Herman Zieschang, Morristown, N. J., assignors to American Telephone and Telegraph Company, a corporation of New York

Application April 7, 1933, Serial No. 665,035

1 Claim. (Cl. 129—38)

This invention relates to improvements in hangers for books, and more particularly to hangers having adjustable characteristics which are adapted to accommodate books of various thicknesses.

It has been customary to suspend books by means of wire structures which have been only adapted for use with books of a certain thickness. Furthermore, such structures involved not alone the use of special tools and time consuming operations in their attachment to books, but also hindered the visibility of the printed matter contained in the books.

Accordingly, it is an object of this invention to provide a book hanger of such flexibility that it is adapted to be attached to books of various thicknesses.

Another object of the invention is to provide a hanger of such construction that it may be conveniently and readily attached to books in a simple and expeditious manner.

A further object is to produce such hangers at a relatively low cost.

The novel features which are considered characteristic of this invention are set forth with particularity in the appended claim. The invention itself both as to its organization and method of operation, together with other objects and advantages thereof, will be further explained in the following detailed description having reference to the accompanying drawing consisting of the following figures:

Figure 1 is a perspective view of the book-engaging elements of the improved device shown as detached from a book.

Fig. 2 is a perspective view illustrating the hanger as attached to a book and in suspended position.

Referring to the drawing, the numeral 5 designates a book having the usual cover which extends about the sides and back of the book and encloses the pages thereof in a well-understood manner. The back of the book has a flat surface against which the surface of a flat strip of metal 6 abuts. The strip 6 is provided on its inner surface with impinging points 7, which engage with the back of the book to assist in maintaining the strip in position thereon. One end 8 of the strip 6 is bent inwardly at an angle to the strip and forms a heel on which the lower corner of the book rests, and the other end of said strip is bent in the opposite direction and connects with a short flat surface 9 which lies in a plane parallel to the strip 6. A central opening is provided in the portion 9 and a slot

10 for the reception of nut 23 may extend outwardly therefrom to the end of said portion. The central opening just mentioned may be elliptical in form to compensate for minor variations in book lengths.

A second strip of flat metal 11 is arranged in a perpendicular plane to the plane of the strip 6. The ends 12 of the strip 11 are bent downwardly toward the back strip 6 to provide a direct clamping action on the ends of the book 5, and the action also increases the impinging action of the points 7, 7 on the back of the book. One end of the strip 11 terminates in a substantially semi-circular plate 13 which lies in a plane parallel to the curved end 8 of the strip 6. The plate 13 and bent end 8 are hingedly engaged with each other and form a pivot about which the strip 11 may rotate. The other end of the strip 11 terminates in a loop portion 14 which is interconnected with a chain 15 by means of a clevis 16 and a bolt. The chain 15 is shown as attached at its other end to the eye of a bolt 17 and may be of sufficient length to permit the book 5 to be suspended at a height at which it may be readily consulted. The bolt 17 extends through an opening in a cup-like portion 18 provided at the outer end of a bracket 19. A helical spring 20 is seated on the portion 18 and surrounds the bolt 17. This spring may be maintained in position by means of a nut carried on the end of said bolt. The bracket 19 is attached to a supporting wall 21.

The strip 11 may be adjustably connected to the strip 6 at the end opposite its hinged joint by means of an elongated link 22 carried by the strip 11. This link is provided with a threaded shank adapted to engage with a nut 23. The nut 23 has an extension which passes through an opening in the flat portion 9 at one end of the strip 6 and this extension carries a collar 24 of larger area than said opening. The collar therefore is seated on the flat portion 9 and prevents the displacement of the nut 23 therefrom. The threaded shank of the loop 22 is of a length to provide a clearance between the strips 6 and 11 to permit a clamping action between the points 7 and the ends 12 of the strip 11.

A book may be mounted in clamped relation between the strips 6 and 11 by applying the strip 6 to the back of the book and rotating and inserting the strip 11 at the approximate middle portion of the pages of the book. The strips may be now forced toward each other and locked together by applying and turning the nut 23 tightly upon the threaded shank of the loop 22. Ten- 55

sion is thus provided by the strips to securely clamp the book between them and lock it in this position. The point 7, 7 on the back strip 6, as previously described, will be caused to firmly impinge the back of the book and prevent the displacement of said strip. When thus positioned between the strips the book may be held suspended from its supporting bracket.

What is claimed is:

- 10 A hanger for books including a pair of elongated flat strips arranged in perpendicular relation with respect to their cross sections and hingedly connected at one of their ends, points

carried by one of said strips near its extremities for engaging the back of a book to hold it in alignment with said strips, terminal portions on the other strip for exerting a clamping action on the ends of the book directly over the engaging points on the first-mentioned strip to hold said book in impinged relation on said points, and locking means permanently engaging one of said strips and adjustably connected to the other strip for holding the free ends of the strips 10 clamped to said book.

JOHN KEMBLE BOLTON.
GUSTAV HERMAN ZIESCHANG.
